SUPPORT

Adolph Lindemann, Chicago, Ill.

Application September 23, 1935, Serial No. 41,716

4 Claims. (Cl. 223—93)

My invention relates to the care of clothing, and includes among its objects and advantages an increase in the security with which the article of clothing may be held on a garment hanger and increased facility in placing such an article on the holder.

In the accompanying drawing:

Figure 1 is a side elevation of a completed device according to the invention;

10 Figure 2 is an enlarged detail of one of the clamping members and associated parts;

Figure 3 is an enlarged detail of the parts inside the housing in Figure 2 with the housing broken away in section;

15 Figure 4 is a section on line 4—4 of Figure 3; and

Figure 5 is a detail of a modification.

In the embodiment of the invention selected for illustration I have indicated a conventional garment hanger bar at 10 and a conventional tension bar at 12 terminating in a hook 14 for hanging it up. The arms 16 are movable from the position indicated in full lines in Figure 1 and in dotted lines in Figure 2 down to the full line position of Figure 2 to clamp a garment suspended from the bar 10 against removal. As the actuating mechanisms for the bars 16 are identical, a description of one will suffice. The housing 18 is pivoted on the bar 10 by means of the fixed pivot 20 and is of a generally U-shaped configuration opening downward with its legs straddling the bar 10. Inside the housing is another U-shaped housing 22 mounted on top of the bar 10 and opening upwardly. The bight of the housing 22 rests directly on the bar 10 and is fastened thereto as by means of the tang 24 turned down from the metal of the bight. The legs of the housing 22 support the second fixed pivot 26, and above the fixed pivot 26 the housing 18 carries a pivot 28, which pivot is movable in response to the rotation of the housing 18 around the pivot 20. Each arm 16 comprises a rigid body portion stiffened by the corrugation at 30. The end of this rigid portion is flat and bent into a semi-circle as indicated at 32 in Figure 3 to engage the movable pivot 28. Riveted to the end of the rigid body portion as at 34 is an extension in the form of a convoluted leaf spring. The leaf spring is curved around the socket 32 as at 36 and then extends in a larger arc at 38 around and under the fixed pivot 26 with a radial end portion 40 terminating in the eye 42 receiving the pivot 26. The parts are assembled with the spring in

5 the pivot 28 away from the pivot 26 with considerable force.

The outer end of each clamping arm 16 is provided with a pad 44. The pad is preferably assembled by slipping it over the end of the arm 16 and then doubling the end portion back under the rest of the arm as clearly indicated at 46.

10 It will be apparent that the parts may be moved from the full line position of Figure 2 to the dotted line position of Figure 2 either by lifting up the arm 16 or by pushing the housing 18 toward the tension bar 12. The housing members 18 each have an upturned ear 48, and the ears 48 can conveniently be grasped between the thumb and one finger and pushed toward each other to move both arms to the open position of Figure 1.

Upon reference to Figure 3 it will be noted that the pivot 26 is slightly to the right of a line joining the pivots 20 and 28 so that the force of the spring 20 portion of the arm will tend to hold the parts in the open position of Figures 1 and 3. Similarly, by pressing downward a little on the arms 16 themselves they may be moved to the clamping position of Figure 2, and in the clamping position 25 the pivot 26 will be materially to the left of a line between the pivots 20 and 28, and the force of the spring 38 will press the pads 44 firmly down upon a garment lying between the pad and the bar 10. The downward movement of the arm 16 30 is limited by engagement of the pad 44 with the bar 10 or with the garment on the bar 10. I have illustrated suitable stop means for limiting the upward movement to the position of Figure 3. The stop means illustrated is an extension 50 at 35 one upper corner of each leg of the housing 22. The socket portion 32 comes in contact with the corner extension 50, as clearly indicated in Figure 3 to limit the opening movement.

40 In using such a device the user can snap the arms 16 to the open position of Figure 1 in an instant, and they will stay there while the user has both hands free to drape the garment over the bar 10. Then a slight downward pressure will move the arms back into the position of Figure 2, either one at a time or simultaneously. This principle of operation affords considerable manipulative advantages, especially in draping a relatively flimsy lady's dress or the like over the bar neatly 45 and without wrinkles.

45 Referring to Figure 5, the housing 18 is shown with an ear 51 projecting toward the tension member 12, and shaped to receive a downward thrust to open the parts. In the open position 55

55 such a condition of stress that it tends to push

the end of the ear 50 engages the tension member 12 to limit the opening movement.

Without further elaboration, the foregoing will so fully explain my invention that others may, by applying knowledge current at the time of application, readily adapt the same for use under varying conditions of service.

I claim:

1. A support comprising, in combination: a curved garment supporting bar; a central connector for supporting said bar; a clamping arm having its inner end adjacent said connector; a pivot fixedly mounted on said bar and carrying the inner end of said arm; a housing enclosing said fixed pivot; a pivot carried by said housing and movable in a path that approaches said fixed pivot at an intermediate point; said arm being also pivoted on said movable pivot; the portion of said arm between said fixed and movable pivots being convoluted and resilient and tending to separate said pivots; the portion of said arm beyond said movable pivot being relatively rigid and extending outwardly; the end of said bar limiting movement of said arm into clamping position; stop means rigid with said fixed pivot for limiting the movement of said arm away from said bar; said housing enclosing said convoluted resilient arm portion and being accessible for manual actuation to move said arm from clamping to open position or vice versa; a duplicate clamping arm, housing, and associated parts on the other side of said connector; said housings having portions exposed to form gripping means for moving both housings toward said tension member to open said clamping arms.

2. A support comprising, in combination: a garment supporting bar; a central connector for

supporting said bar; a clamping arm having its inner end adjacent said connector; a pivot fixedly mounted on said bar and carrying the inner end of said arm; a pivoted housing enclosing said fixed pivots; a pivot carried by said housing and movable in a path that approaches said fixed pivot at an intermediate point; said arm being also pivoted on said movable pivot; the portion of said arm between said fixed and movable pivots being convoluted and resilient and tending to separate said pivots; the portion of said arm beyond said movable pivot being relatively rigid and extending outwardly; the end of said bar limiting movement of said arm into clamping position; said housing enclosing said convoluted resilient arm portion.

3. A support comprising, in combination: a garment supporting bar; a clamping arm; a pivot fixedly mounted on said bar and carrying one end of said arm; a pivot movable in a path that approaches said fixed pivot at an intermediate point; said arm being also pivoted on said movable pivot; the portion of said arm between said fixed and movable pivots being resilient and tending to separate said pivots.

4. A support comprising, in combination: a garment supporting bar; clamping arms having their inner ends adjacent; a pivot for the inner end of each arm mounted on said bar; a housing enclosing each fixed pivot; a pivot carried by each said housing and movable in a path that approaches the adjacent fixed pivot at an intermediate point; each arm being pivoted also on its movable pivot; the portion of each arm between its fixed and movable pivots being convoluted and resilient and tending to separate said pivots.

ADOLPH LINDEMANN.
